UNITED STATES PATENT OFFICE

170,117

ELECTRIC RANGE

Folke M. Gustafson, Toledo, Ohio, assignor to
Avco Manufacturing Corporation, Cincinnati,
Ohio, a corporation of Delaware

Application December 20, 1952, Serial No. 22,802

Term of patent 14 years

(Cl. D81—4)

To all whom it may concern:

Be it known that I, Folke M. Gustafson, a citizen of the United States, residing at Toledo, Ohio, in the county of Lucas, have invented a new, original, and ornamental Design for an Electric Range, of which the following is a specification, reference being had to the accompanying drawing, forming a part thereof.

The figure is a perspective view of an electric range embodying my new design. The left end of the range, not visible in the drawing, is substantially the same as the right end which is shown.

The design for the electric range disclosed is characterized by the backguard panel and

the handles having the configurations shown.

I claim:

The ornamental design for an electric range, as shown and described.

FOLKE M. GUSTAFSON.
